P. O. MAMOCK.
PISTON RING EXPANDER AND REMOVER.
FILED NOV. 12, 1921.

UNITED STATES PATENT OFFICE.

PAUL O. MAMOCK, OF RASPEBURG, MARYLAND.

PISTON-RING EXPANDER AND REMOVER.

Application filed November 12, 1921. Serial No. 514,673.

To all whom it may concern:

Be it known that I, PAUL O. MAMOCK, a citizen of the United States, residing at Raspeburg, in the county of Baltimore and State of Maryland, have invented certain new and useful Improvements in Piston-Ring Expanders and Removers, of which the following is a specification, reference being had to the accompanying drawings.

It is a purpose of the present invention to provide a device of this kind capable of expanding and removing piston rings of various diameters.

Another purpose consists in the provision of a piston ring expander and remover wherein a pair of opposed members is provided having arms so shaped as to engage about the ring and including clamps or jaws upon the arms adjustable so as to engage with piston rings of different diameters, whereby a pair of pins carried by the terminals of the arms may engage the notches in the piston ring for expanding it sufficiently to remove it from the piston.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view in elevation showing the improved piston ring expander and remover constructed in accordance with the invention, showing the opposed members or jaws thereof as having been moved, in dotted lines;

Figure 2 is a view in elevation of the piston ring expander and remover, showing the clamps as having been adjusted to engage a piston ring of a smaller diameter.

Figure 3 is a plan view of the adjacent end portions of the two jaws of the opposed members, showing the pins engaging with the notches at the ends of the piston ring;

Figure 4 is a sectional view on line 4—4 of Figure 1; and

Figure 5 is a detail view of one of the members, showing how a connecting bar be-

tween the members engages through the slot in the handle of one of the members.

Referring to the drawings, 1 and 2 designate the opposed members of the ring expander and remover. Each member comprises a handle portion 3 terminating in a part 4 extending at an obtuse angle to the handle portion. The part 4 merges into an extension 5 which extends substantially at right angles to the part 4. The extension 5 terminates in the curved portion 6. The opposed members 1 and 2 are arranged relatively to each other so that the terminals of the curved portions 6 abut, there being a bar or plate 7 passing through slots 8 adjacent where the handles merge into the portions 4. Suitable cotter pins 9 engage through openings 10 adjacent the ends of the bar or plate 7 to limit the outward movement of the handle. A coil spring 11 surrounds the bar 7 and is adapted to expand sufficiently to hold the handles against the cotter pins.

The adjacent terminals 12 of the curved portions 6 have transversely disposed pins 13. It will be noted that these pins are in alignment, that is when the terminals 12 are in alignment. However, when the opposed members are expanded or moved apart and engaged about the ring, the terminals are sprung slightly laterally from each other, so that the pins 13 may engage the notches 14 of the adjacent ends of the piston ring. This may be accomplished by causing one pin 13 to first engage one of the notches, then the other terminal is moved in the opposite direction to cause the other pin 13 to engage the opposite notch 14. This is accomplished when the opposed members are engaged in position about the piston. Upon pressing the handles of the opposed members toward each other against the action of the coil spring 11, the opposed members will mainly fulcrum at points substantially 15 degrees below an imaginary center line of the piston ring, say for instance about 15 degrees below the line a—a. Although this is about the true fulcruming point for the opposed members, they also have a fulcruming action upon the bar 7. The fulcruming action on the bar 7 is not a fixed fulcrum, but due to the bar loosely engaging through the handles, the fulcrums are changeable or variable. When the terminals of the curved portions 6 of the arms separate sufficiently, the adjacent ends of the piston ring will be likewise separated,

the ring may be expanded far enough so that it will be lifted easily over the piston. After the ring is disengaged from the piston it may be detached from the pins 13 and placed 5 to one side. Each piston ring may be removed in a similar manner.

Piston ring abutments 15 are mounted upon the portions 5 of the arms of the opposed members and are adapted to engage 10 with the piston ring at points fifteen degrees below an imaginary line passing horizontally across the diameter of the piston ring, as indicated by the line $a-a$ in Figure 1. These abutments act to prevent the terminals 15 of the piston ring from disengaging the pins 13 when the arms are separated sufficiently to open the ends of the ring. Each abutment comprises a pair of opposed plates 16 constructed of any suitable material, preferably 20 sheet metal, clamped together by means of a screw bolt 17 and nut 18. The plates 16 have arms 19 which engage the opposed edges of the portion 5 of one of the opposed members, as shown clearly in Figure 4. Obviously by tightening up the nut 18, the opposed plates 16 may be drawn together securely to hold the abutments in different positions upon the portion 5. The other ends of the plates 16 terminate in arms 20 which 30 are of angular contour adapted to engage the opposite edges of the piston ring, particularly when the diametrically opposed portions of the ring are being expanded. The right angled disposed terminals of the arms 35 20 of the plates 16 act to prevent lateral movement of the piston ring, during its expanding movement, when the opposed members are in the act of separating the terminals of the ring. Obviously the abutments 40 may be adjusted along the portions 5 of the arms of the opposed members, so that the right angled arms 20 may engage piston rings of different diameters. In fact, the arms or portions 20 have their flanged portions extending at obtuse angles to the portions 5 of the arms of the opposed members 45 1 and 2, so that the portions 20 may engage the piston ring at points substantially fifteen degrees below an imaginary horizontal line, as indicated at $a-a$ in Figure 1, so as not only to prevent lateral movement of the piston ring but also to prevent movement of the ring in a direction toward the handles.

To engage the piston ring expander with 55 the ring, it is held in one hand with the handles as far apart as the cotter pins 9 will allow. The device is then slipped over the piston and the pins 13 are engaged in the notches 12 of the adjacent ends of the ring. 60 The handles are then pressed together until the ring has expanded enough to be slipped over the piston. While the opposed handles in a sense have changeable fulcrums on the bar 7, the sole purpose of the bar 7 is to 65 unite the opposed members so as to construct

the device as one unit. It may be noted that the opposed members may act as well without the bar 7 and the spring, and if it is possible to imagine the device operated in this manner, a better understanding of the working parts of the same may be attained.

The invention having been set forth, what is claimed is:

1. In a piston ring expander and remover, a pair of opposed members, a bar upon 75 which the members are yieldably connected, said members having arms of angular contour adapted to engage a piston ring, the terminals of the arms being curved and normally abutting and provided with means for 80 engagement with the diagonally disposed notches of the piston ring whereby, upon a separating movement of the terminals of the arms, the ends of the piston ring may become separated, and means upon the arms 85 adapted to engage the piston ring at points substantially fifteen degrees below an imaginary horizontal line passing through the axis of the piston ring, thereby preventing the notched terminals of the ring from disengaging the ring engaging means on said arms.

2. In a piston ring expander and remover, a pair of opposed members having jaws for 95 engaging opposite portions of a piston ring, fulcrumed connecting means for the members, the jaws having opposed terminals provided with means for engagement with diagonally opposed notches of the piston ring for separating the ends of the ring, and 100 abutment means adjustable on the jaws and adapted to engage piston rings of different diameters at points below an imaginary horizontal line passing through the axis of the ring to prevent disengagement of the 105 notched terminals of the ring from the notch-engaging means of the jaws.

3. A piston ring expander and remover comprising a pair of opposed jaws adapted 110 for engagement with opposed parts of a piston ring, means for operatively connecting said jaws, said jaws having adjacent terminals, means carried thereby for engagement with the notches at the terminals of the piston ring for expanding the piston ring terminals, and means on the jaws to prevent the piston ring terminals from disengaging the notch engaging means.

4. A piston ring expander and remover comprising opposed operatively connected 120 jaws adapted to engage opposed parts of a piston ring, abutment means adjustable upon the jaws and provided with means to embrace a piston ring at points below a horizontal line passing through the axis of the 125 ring, said jaws adjacent their terminals being provided with means to engage the terminals of the piston rings, thereby cooperating with the abutment means for expanding and removing the piston ring.

5. A piston ring expander and remover comprising a pair of opposed jaws having terminals adapted for engagement with opposed parts of a piston ring for expanding the piston ring, means for operatively yieldingly connecting said jaws, and means on the jaws to prevent the opposed parts of the piston ring from disengaging the terminals of the jaws.
6. A piston ring expander and remover comprising opposed operatively connected jaws having terminals adapted to engage opposed parts of a piston ring, abutment means adjustable upon the jaws and adapted to engage a piston ring at points below an imaginary horizontal line passing through the axis of the ring, thereby cooperating with the jaw terminals in expanding and removing the piston ring.
7. In a piston ring expander and remover, a pair of opposed members having jaws provided with means for engagement with the opposed parts of the piston ring for separating the ends of the ring, and means operatively connecting the members, abutment
- means adjustable on the jaws adapted to engage the piston ring at points below an imaginary horizontal line passing through the axis of the ring to prevent the opposed parts of the ring disengaging the ring-engaging means of the jaws.
8. In a piston ring expander and remover, a pair of opposed members having arms adapted to embrace a piston ring, the terminals of the arms being curved and provided with means for engagement with the piston ring, whereby upon a separating movement of the terminals of the arms the ends of the piston ring are separated, a yieldable connection between the members, and means upon the arms adapted to engage the piston ring at points below an imaginary horizontal line passing through the axis of the piston ring, thereby preventing the ring from disengaging the ring engaging means on said arms.

In testimony whereof I hereunto affix my signature.

PAUL O. MAMOCK.
